HYPODERMIC CARTRIDGE UNIT

Warn G. Menhennett, Cochranville, and William F. Elias,
West Chester, Pa., assignors to American Home Products Corporation, New York, N.Y., a corporation of Delaware

Filed Jan. 23, 1967, Ser. No. 5,533

Term of patent 14 years

(Cl. D83—12)

FIG. 1

FIG. 2

FIG. 3

FIG. 4

FIG. 5

FIG. 1 is an elevation of a hypodermic cartridge unit embodying our new design;

FIG. 2 is an elevation of a modified embodiment of the hypodermic cartridge unit shown in FIG. 1;

FIG. 3 is a further modified embodiment of a hypodermic cartridge shown in FIG. 1;

FIG. 4 is a top plan view of the embodiment of FIG. 1; and

FIG. 5 is a bottom plan view of said embodiment of FIG. 1.

We claim:

The ornamental design for a hypodermic cartridge unit, as shown.
